UNITED STATES PATENT OFFICE.

HERBERT G. IRWIN, OF AMARILLO, TEXAS.

VALVE-CONTROLLING MECHANISM FOR ACETYLENE GENERATORS.

Application filed December 12, 1921. Serial No. 521,827.

To all whom it may concern:

Be it known that I, HERBERT G. IRWIN, a citizen of the United States, residing at Amarillo, in the county of Potter and State of Texas, have invented certain new and useful Improvements in Valve-Controlling Mechanism for Acetylene Generators, of which the following is a specification.

The present invention relates to valve controlling mechanism for acetylene generators and is designed especially to automatically equalize the rate of generation and consumption of the gas to avoid waste and make the pressure of gas constant.

Another object of the invention is to provide a device of this character which is simple in construction and which may be associated with acetylene generators of standard construction without excessive cost and without the expenditure of undue labor.

The above and other objects of this invention will be partly described and partly understood from the following description of the present preferred embodiment of the invention taken in connection with the accompanying drawings wherein:

Fig. 1 is a vertical sectional view of an acetylene generator embodying this invention, a portion of the invention being shown in side elevation;

Fig. 2 is a vertical sectional view of the valve controlling mechanism per se;

Fig. 3 is a perspective view of the diaphragm which forms a part of the valve controlling mechanism;

Fig. 4 is a perspective view of one of the movable tubes which also forms a part of the valve controlling mechanism; and

Fig. 5 is a perspective view of a tube which telescopes the tube shown in Fig. 4 and forms a part of the valve controlling mechanism.

In the drawings an acetylene generator is shown which may be of the usual or any desired configuration. In the present instance in order to illustrate the application of this invention, a cylindrical water tank 6 is shown in which is mounted a conically shaped carbide hopper 7. The upper marginal edge of the receptacle is bent over to receive a correspondingly formed portion on the upper marginal edge of the carbide hopper. The apex of the hopper is provided with an opening to permit gravitation of the carbide from the hopper and into the water receptacle.

In order to normally close communication

through the carbide hopper, a conical valve 8 is provided which is movably mounted in the opening formed in the apex of the carbide hopper. The valve is of an inverted cone shape and has a stem 9 issuing from its apex which is slidably arranged through a guide 10. The guide 10 is supported by a bracket 11 which latter is fixedly secured to the inner periphery of the carbide hopper. The valve stem 9 has its upper end extended beyond the upper end of the guide 10 and into a housing 12. A coil spring 13 is convoluted on the upper end of said valve stem above the guide 10 and is encased by the housing 12. This spring has one end thereof engaged with the upper end of the valve stem and the opposite end engaged with the upper end of the guide 10 to normally hold the valve 8 in a closed position.

Secured to the upper outer periphery of the water receptacle 6 is a right angled flange 14 which has upstanding therefrom a plurality of bolts 15. These bolts extend through a closure 16 mounted upon the top of the carbide hopper 7 so as to clamp the closure, carbide hopper and water receptacle snugly in engagement. The closure is equipped with a concentric upstanding nipple 17 provided with internal screwthreads.

A valve controlling mechanism generally designated 18 is mounted on the closure 16 and in the present instance consists of a relatively short outer tube 19 provided with external screwthreads which are engaged with the internal threads of the nipple 17. The tube 19 is provided, approximately midway its ends, with an annulus 20. An elongated tube 21 is telescopically mounted in the tube 19 and is of a diameter relatively smaller than the diameter of the interior of the tube 19 so as to provide a space between the outer periphery of the tube 21 and the inner periphery of the tube 19. The lower end of the tube 21 normally extends appreciably below the lower end of the tube 19 and is equipped with an annular abutment 22 which is detachably mounted in a corresponding groove in said tube. An annulus 23 is formed on said inner tube adjacent the upper end of the latter. The annulus 23 is identical in configuration with the annulus 20 and is positioned above the upper end of the outer tube 19. Movably mounted through the inner tube 21 is a shaft 24 the lower end of which has screwthreads 25 formed thereon

which engage corresponding threads formed on the inner periphery of the inner tube 21 at the lower end of the latter. A nut 26 is adjustably mounted on the threads 25 and 5 capacitates as an abutment to limit upward movement of the shaft 24. The upper end of said shaft is formed to provide a handle 27 through the medium of which the shaft is rotated. The shaft 24 extends through a 10 packing gland 28 detachably mounted on the upper end of the inner tube 21. A diaphragm 29 is mounted between annuli 20 and 23. This diaphragm consists of a series of flexible plates the margins of which are 15 flexibly sealed together and equipped with marginal binders 30 to produce a substantially unit structure which is normally contracted due to its inherent properties and construction. The upper and lower plates 20 of the diaphragm have their upper margins bent over the annuli 20 and 23 to effectively hold the diaphragm from displacement. The binders on the inner margins of the plate provide relatively large rings through which 25 the tubes 19 and 21 are concentrically mounted.

In use of this device the valve 8 is normally held in a closed position by the contractile action of the spring 13. In order 30 to permit gravitation of the carbide from the hopper 7 into the receptacle 6, in the proper volume, the shaft 24 is rotated thereby forcing the valve stem 9 downwardly against the resistance of the spring 13 to 35 unseat the valve 8. The gas generated by the admixture of carbide and water is permitted to rise upwardly by the carbide feed valve 8 between the tubes 19 and 21 and into the diaphragm structure causing same 40 to expand upwardly carrying the tube member 21 and shaft 24 allowing the valve 8 to close thereby discontinuing the feed of carbide. The diaphragm structure acting in the capacity of a spring against the gas 45 pressure within the generator body, requires a relatively high degree of pressure to fully inflate or expand the structure. Therefore, it will be seen that various degrees of pressure may be had by screwing 50 the shaft 24 further down which will hold the valve 8 open until enough carbide has entered the receptacle 6 to create a pressure sufficient to expand the diaphragm structure further and allow the valve 8 to close. 55 As the gas is consumed from the generator the pressure is lowered accordingly which will tend to deflate the diaphragm structure which will open the carbide feed valve with obvious results. It will be seen that in this 60 method of construction the several diaphragm plates act in series. Each diaphragm plate expands away from the other, whereas the movement of one plate is augmented by movement of the others throughout the column. This action will impart a

movement to the tube member 21 equal to the movement of the several plates taken collectively, which will obviously operate the carbide feed valve 8 by a slight variation of pressure. It is of course apparent 70 that upward movement of the inner tube 21 is limited by the abutment 22 which will contact with the lower end of the outer tube 19 thereby preventing undue distention of the diaphragm. It will be understood from 75 the above that the action of the valve controlling mechanism is automatic and is controlled entirely by variation in the gas pressure as above described. If desired a housing 31 may be sleeved on the outer tube 21 below the gland 28 and engaged with the closure 16 so as to encase the diaphragm and other elements associated therewith which are positioned on top of the closure. 80

Various changes may be made in this device without departing from the spirit and scope of this invention since I have herein attempted to describe only one form of the invention whereas the device is capable of use in other capacities with slight modification. This form of the invention, however, 85 covers the principle of using a mechanically adjustable valve to control the volume of carbide into the water tank, the mechanical adjustment being servient, however, to 90 the automatic operation of the diaphragm under influence of the gas. 95

What is claimed is:—

1. Valve controlling mechanism for acetylene generators, in combination with water 100 and carbide chambers equipped with an interposed normally closed carbide feed valve, means for controlling said valve including a pair of annuli, a tube carried by each annulus, said tubes being telescoped and spaced 105 to provide a passageway therebetween, a series of flexible disks arranged between said annuli and provided with central openings through which said tubes extend, said disks being dished to alternately dispose 110 the inner and outer margins of adjacent disks in contiguity, the terminal disks of 115 said series being sealed to said annuli and the contiguous margins of the disks sealed together, and a feed valve engaging rod carried by one of said tubes, the other tube being fixed on the water chamber whereby gas from the carbide chamber passes between the tubes and into contact with said disks to expand the latter and disengage the valve 120 rod to allow the carbide feed valve to close.

2. In combination with a water receptacle and a carbide feed hopper and a valve normally closing communication between said receptacle and hopper, a stationary tube 125 carried by the water receptacle, an inflexible disk mounted on the tube, a tube movably arranged in the first tube and spaced therefrom to permit the passage of gas between said tubes, a second inflexible disk 130

mounted on said movable tube, a plurality of alternately inverted frusto-conical flexible rings disposed between said disks, the contiguous margins of said rings being sealed together and the terminal rings engaged with said disks to provide a gas re-

ceiving diaphragm, and means carried by the movable tube and in operative connection with said valve to release the latter when said diaphragm is flexed under the influence of the gas. 10

HERBERT G. IRWIN.
